UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING-SALESBOOK.

1,381,446.

Specification of Letters Patent. Patented June 14, 1921.

Application filed July 7, 1920. Serial No. 394,503.

To all whom it may concern:

Be it known that I, EDWARD K. BOTTLE, a citizen of the United States, residing at Elmira, in the county of Chemung and State 5 of New York, have invented certain new and useful Improvements in Manifolding-Salesbooks, of which the following is a full, clear, and exact description, such as will enable others skilled in the art to which it appertains to make and use the same.

This invention relates to manifolding devices, and with respect to its more specific features to manifolding books, as sales books and the like.

15 The objects of the invention are the provision of a practical manifolding sales book in which four records may be made at one writing and in which three of the records are connected to each other and may be detached, as one, from the book, and in which relatively few transfer sheets are required.

20 Other objects will be in part obvious and in part pointed out hereinafter.

The invention accordingly consists in the 25 features of construction, combinations of elements and arrangement of parts which will be exemplified in the construction hereinafter set forth, and the scope of the application of which will be indicated in the following claims.

30 In the accompanying drawing forming part of this specification, and in which similar reference characters refer to similar parts throughout the several views, there is 35 illustrated a perspective view, largely diagrammatic, of a sales book embodying the invention.

35 The numeral 1 indicates a support, as, for instance, a flexible manila sheet. The numeral 2 indicates a pad having a stub portion 3, the pad being hinged to the support 1 at the end opposite its stub, as at 4, the pad being provided with a suitable back 5 which is relatively stiff, being composed of heavy 45 cardboard.

40 The pad 2 comprises a series of superposed sets of record leaves, the topmost set being indicated by the numerals 6, 7 and 8, of 45 which the leaf 7 is attached to the stub portion and provided with a weakened line 9 for ready separation from the stub, the leaves 6, 7 and 8 being of opaque manifolding material and attached together at one end 10 remote from, or opposite the stub 3.

The leaves 6 and 7 may be formed of an 55 integral sheet folded on itself as at 10 and weakened at the fold 10 so that these two leaves may be readily torn apart, the third leaf 8 being pasted to one or the other of the leaves 6 and 7 near the fold line therebetween. In the present embodiment the inter-sheet, or leaf 8, is pasted to the inner face of the leaf 7 and lies between the leaves 6 and 7. Thus each set of leaves includes an 60 original leaf 6, a duplicate leaf 7, and a 65 triplicate leaf 8, the original being the leaf on which the inscription is directly made and the duplicate and triplicate having transmitted thereto, through suitable transfer material, the inscription made upon the 70 original leaf. It is to be understood that the pad 2 is made up of superposed sets of leaves like those described above for the topmost set, one leaf of each set being attached to the stub.

75 The numeral 11 indicates a fourth, or quadruplicate, record leaf which is adapted to lie between two of the other leaves. The quadruplicate leaf may be composed of either opaque or translucent manifold material, but in the present instance is of translucent material, as tissue or parchment. The leaves 11 form a pad attached to the support leaf 1 at a part remote from the hinge of pad 2 and along lines parallel to 80 the stub 3.

85 The numerals 12 and 13 indicate two leaves of transfer material, as, for instance, carbon leaves in superposed relation adapted to be disposed to transfer impressions from 90 the original to the other leaves of a set. In the present embodiment the carbon leaf 12 is single faced; that is to say, it is carbonized on its under face only, whereas the upper transfer leaf 13 is double faced, being carbonized on both its upper and lower faces, both transfer leaves 12 and 13 being connected to the stub of the pad 2 and adapted to lie between the record leaves. The leaves 95 11 are embodied in a second pad, the stub of 100 which is indicated at 14 stapled to that end of the support 1 which is adjacent the stub 3 of the other pad, the several leaves 11 being adapted to lie upon the pad 2 or between the leaves of the topmost set thereof.

105 In setting the book one of the transfer leaves is disposed between the duplicate and triplicate leaves 7 and 8 and another be-

tween the original leaf 6 and the triplicate leaf 8. Thereupon, the leaves 11 being thrown back into the position shown in the drawing, the under leaf 11 is placed between 5 the original and triplicate leaves 6 and 8 and directly against the upper carbon face of the transfer sheet 13. The operative or set position of the book is illustrated in the drawing, except that the parts are somewhat 10 removed from normal position for clearer disclosure of the relationship therebetween. The operator inscribes the outer face of the original leaf 6 and the inscription will be transferred to the duplicate, triplicate, and 15 quadruplicate leaves the inscription upon the quadruplicate leaf being on the under side thereof and reversed but readily read by looking through the quadruplicate leaf which is transparent or translucent in order 20 to permit its being read in this manner. The inscription having been made, the pad 2 may be lifted by grasping its stub portion 25 and turning it around the hinge line 4, whereupon the inscribed quadruplicate leaf will be withdrawn from between the leaves of the pad 2 and will fall on to the support 1 and be covered and protected by the pad 2 when this pad is restored to position. 30 Thereupon the outer end of the three connected leaves 6, 7 and 8 may be grasped and together separated from the stub by tearing the lower leaf 7 along the weakened line 9. The pad is then ready to be set for another 35 inscription.

Thus by the above described construction are accomplished, among others, the objects hereinbefore referred to.

As many changes could be made in the above construction and many apparently 40 widely different embodiments of this invention could be made without departing from the scope thereof, it is intended that all matter contained in the above description or shown in the accompanying drawing shall 45 be interpreted as illustrative and not in a limiting sense.

It is also to be understood that the language used in the following claims is intended to cover all of the generic and specific 50 features of the invention herein described, and all statements of the scope of the invention which, as a matter of language, might be said to fall therebetween.

Having described my invention, what I 55 claim as new and desire to secure by Letters Patent is:

1. A manifolding book comprising, in combination, a series of sets of leaves for manifold copies, each set including an original leaf, a duplicate leaf and a triplicate leaf 60 attached together at one end, one of the leaves of each set being attached to the stub portion, a quadruplicate leaf adapted to lie between two of said first mentioned leaves, 65 and transfer material disposed to transfer

impressions from the original to the other leaves of a set, including a double faced transfer leaf between said quadruplicate leaf and the next underlying manifold leaf.

2. A manifolding book comprising, in combination, a series of sets of leaves for manifold copies, each set including an original leaf, a duplicate leaf, and a triplicate leaf attached together at one end, one of the leaves of each set being attached to the stub 75 portion, a quadruplicate leaf adapted to lie between two of said first mentioned leaves, and transfer material disposed to transfer impressions from the original to the other leaves of a set including a double faced 80 transfer leaf between said quadruplicate leaf and the next underlying manifold leaf, said quadruplicate leaf being translucent.

3. A manifolding book comprising, in combination, a support, a pad hinged to said support at the end opposite its stub, said pad comprising a series of sets of leaves for manifold copies, each set including an original leaf, a duplicate leaf, and a triplicate leaf attached together at one end opposite the 90 stub portion of such pad, one of the leaves of each set being attached to the stub portion, a second pad of translucent leaves the stub portion of which is attached to said support to lie adjacent the stub of the first 95 mentioned pad, whereby the leaves of said second mentioned pad are adapted to lie between the leaves of the first-mentioned pad, and two transfer leaves connected to said first mentioned pad, one adapted to lie between the duplicate and triplicate leaves, and the other being double faced and adapted to lie between the translucent and the triplicate leaves. 100

4. A manifolding book comprising, in combination, a support, a pad having a stub and hinged to said support at the end opposite its stub, said pad comprising a series of sets of leaves for manifold copies, each set including an original leaf, a duplicate leaf, and a triplicate leaf attached together at one 105 end, one of the leaves of each set attached to said stub, a second pad of leaves attached to said support at a part remote from said hinge and adjacent to said stub and along a 110 line parallel to said stub, whereby the leaves of said second pad may be interleaved with either pair of said leaves of said first mentioned pad, and may lie either above or below said first mentioned pad, and two transfer leaves connected to the stub end of said 115 first-mentioned pad in superposed relation, the uppermost of said transfer leaves being double faced.

In testimony whereof I affix my signature 125 in the presence of two witnesses.

EDWARD KIRBY BOTTLE.
